PLAY TOWER

Daniel P. Grudoski, Hartstown, Pa.
Filed Aug. 22, 1962, Ser. No. 71,407

Term of patent 14 years

(Cl. D34—5)

The FIGURE is a perspective view of the play tower showing my new design.

The sides not fully shown are substantially similar in external appearance to those sides which are fully shown.

I claim:

The ornamental design for a play tower, as shown and described.
